COIL STRUCTURE

Filed Aug. 21, 1931

UNITED STATES PATENT OFFICE

GIUSEPPE RIGANTE, OF WESTERLEIGH, STATEN ISLAND, NEW YORK

COIL STRUCTURE

Application filed August 21, 1931. Serial No. 558,596.

The present invention relates to new and useful improvements in electrical devices, and more particularly it pertains to a coil structure.

5 It is the primary object of the invention to provide a new and novel construction of coil which will be simple in construction and easy of manufacture.

A further object of the invention resides 10 in a new and novel means for supporting a coil in operative position.

A still further object of the invention resides in the provision of a novel construction whereby the coil may be made of various diameters.

With the above and other objects in view, reference will be had to the accompanying drawings, illustrating the invention in a preferred form, and in which,

20 Figure 1 is a longitudinal sectional view of a coil constructed in accordance with the present invention,

Figure 2 is a transverse sectional view taken on the line 2—2 of Figure 1,

25 Figure 3 is a detail perspective view of one portion of the coil,

Figure 4 is a detail perspective view of another portion of the coil,

30 Figure 5 is a detail view in elevation, on a reduced scale illustrating one manner of supporting the coil,

Figure 6 is a similar view illustrating another manner of supporting the coil, and;

35 Figure 7 is a detail sectional view illustrating the manner in which the leads may be attached to the coil element.

Referring more particularly to the drawings, the coil comprises an inner body member 10 and this body member is preferably of 40 cylindrical cross sectional form and is elongated. The body 10 has radially extending spaced flanges 11 which extend longitudinally thereof as best illustrated in Figure 4.

45 Extending longitudinally through the body 10 there is an opening 12, the purpose of which will be hereinafter described.

The body 10 forms the means about which 50 a coil of wire or suitable conducting material 13 is wound as best illustrated in Fig-

ures 1 and 2, and this coil 13 may form one of the coils of an induction coil.

The reference character 15 designates end members which are preferably circular in form, and have notches 16 formed in their periphery. The end members have centrally disposed openings 17, and these openings 17 are adapted to receive a bolt, rod or the like 18 which extends through the passage 12 of the body 10, and is provided with a suitable nut or the like 19 by which the end members 15 may be secured to the body 10.

The end members 15 are of larger diameter than the diameter of the body member 10, and mounted in the notches 16 thereof, there are 60 longitudinally extending bars or the like 25. These bars 25 are so shaped in cross sectional form as to be removably received within the notches 16 and by reason of the increased diameter of the end members 15 said bars will 65 be mounted in spaced relation with respect to the coil 13 as indicated by the reference character 26 in Figure 2. The bars 25 form the means for supporting a second coil 28 which is wound therearound and said bars 70 support the coil 28 in spaced relation with respect to the coil 13, as best illustrated in Figure 2 of the drawings. The end members 15 may be provided with a plurality of openings 30 through which the leads of the inner 75 and outer coils may be passed as illustrated in Figure 2 of the drawings.

Thus it will be apparent that an induction coil of a simple construction is provided, it being understood that the body member 10, the end members 15 and the bars 25 are formed from suitable non-conducting material.

When it is desired to produce a coil which is circular in cross section, the bars 25 are 80 employed as illustrated in the drawings. If, however, it is desired to form a coil which is angular in cross section, alternate bars 25 may be removed, and the outer coil 28 formed about half the number of bars illustrated 85 in the drawings, in which case the outer coils would assume a square cross sectional shape.

The coil may be supported by the bolt or the like 18, and for this purpose a brack- 90

et 40 is employed. The bracket 40 comprises a body portion 41 having two end members 42 and 43, the end member 43 terminating in a right angular portion 44. The portion 42 is provided with an opening 45 and the portion 44 is provided with an opening 46.

By this construction of bracket, it is apparent that the coil may be supported in either a horizontal plane as illustrated 10 in Figure 6, or in a vertical plane as illustrated in Figure 5, all by the same socket, merely by selective use of the openings 45 and 46.

In Figure 7 I have shown a slightly modified form of connecting the leaves, and in 15 this figure, the coils 13 and 28 terminate in binding posts or the like 50, and suitable leaves 51 are connected to these binding posts.

From the foregoing it will be apparent that the present invention provides a new 20 and novel construction of electric coil, and also that the invention provides a new and novel means for supporting coils in electrical apparatus.

While the invention has herein been illustrated in its preferred forms, it is to be understood that the invention is not to be limited to the specific construction herein shown, and that it may be practiced in other forms 25 without departing from the spirit thereof.

Having thus described the invention, what 30 I claim as new and desire to secure by Letters Patent is:—

1. An electrical coil structure comprising a body member having longitudinally extending radial flanges, an electrical conductor wound around said body member to form a coil, end pieces secured to said body member, longitudinally extending spaced bars carried by said end members and spaced from 35 said body member, and an electrical conductor wound around said bars to form a coil.

2. An electrical coil structure comprising an elongated body member, radially disposed flanges extending longitudinally of said body 40 member, end members, means for securing said end members to said body member, bars extending longitudinally of said body member in spaced relation thereto, and being removably carried by said end members, a coil formed about said body member, and a second coil formed about said bars.

3. An electrical coil structure comprising an elongated body portion of substantially 45 circular cross-sectional form, radially projecting flanges extending longitudinally of said body portion, notched end members of larger diameter than the diameter of the body portion, means for securing said notched end members to the ends of the body portion, longitudinally extending bars carried in the notches of the end members, a coil formed about the flanges of the body member, and a second coil formed about the bars carried 50 by the end members.

4. An electrical coil structure comprising

an elongated body portion of substantially circular cross-sectional form, radially projecting flanges extending longitudinally of said body portion, notched end members of larger diameter than the diameter of the body portion, means for securing said notched end members to the ends of the body portion, said means including a bolt extending longitudinally through the body members, longitudinally extending bars removably carried in the notches of the end members, a coil formed about the flanges of the body member, and a second coil formed about the bars carried by the end members.

In testimony whereof I affix my signature. 55
GIUSEPPE RIGANTE.
